DESIGN FOR A FINGER GUARD, FOR SLICING VEGETABLES, MEATS, OR THE LIKE

Leo Körmendy, Detroit, Mich.

Application April 3, 1939, Serial No. 84,006

Term of patent 3½ years

To all whom it may concern:

Be it known that I, Leo Körmendy, a citizen of the United States, residing at Detroit, in the county of Wayne and State of Michigan, have invented a new, original, and ornamental Design for a Finger Guard, for Slicing Vegetables, Meats, or the like, of which the following is a specification, reference being had to the accompanying drawing, forming part thereof.

Fig. 1 is a front elevational view of a finger guard, for slicing vegetables, meats or the like;

Fig. 2 is a side elevational view;
Fig. 3 is a rear elevational view;
Fig. 4 is a top plan view thereof, and
Fig. 5 is a perspective view, showing my new design.

I claim:

The ornamental design for a finger guard, for slicing vegetables, meats, or the like, as shown.

LEO KÖRMENDY.
